GLASS-GATHERING APPARATUS AND METHOD

Application filed July 16, 1917. Serial No. 180,795.

My invention relates to apparatus for and methods of delivering glass in molten form from a tank furnace or other receptacle, and discharging the glass in proper amounts as 5 to weight and in proper shape and condition for fabricating into bottles, sheets and for other purposes.

In a general way, apparatus of the invention comprises two main parts:—First, a delivery apparatus for taking the molten glass from a tank furnace or other supply body and transferring it into a receptacle; and second, a receptacle which is so constructed and arranged as to deliver quantities of glass in 15 exact size and of proper weight, shape and condition for final working.

The objects of my invention are:

1st. To provide a practical means for and method of delivering molten glass in proper 20 condition to be formed into bottles and other objects;

2nd. A more specific object is to do this work in such a way that the apparatus can be used in conjunction with the standard semi-automatic bottle machines and presses which 25 are in general use.

In order to accomplish these objects, especially the second, it is necessary to so construct and arrange my apparatus that it will 30 duplicate the work of the hand gatherer by mechanical means, so that it will not be necessary for the manufacturer or user to remodel his present machines, or change his methods, which have been developed to meet 35 the various limitations of speed, etc., which manual work entails.

With these and other objects in view, the invention consists in the construction and arrangement of parts, and in the method of 40 using the same, which is illustrated in the accompanying drawings, in which Fig. 1 is a vertical section, parts being in elevation, of an apparatus embodying my invention; Fig. 2 is a detail of certain cam members of the device; Figs. 3 to 7, inclusive, are views in section illustrating various stages or steps in the operation of the device; Fig. 8 is a view of a modification of the parts shown in 45 Figs. 3 to 7; Figs. 9 to 13, inclusive, are 50 views in section illustrating another modifi-

cation of the apparatus; and Figs. 14 and 15 are views in section showing still further modifications.

In the embodiment of my invention herein selected for illustration, and referring first 55 to Figs. 1 to 6, inclusive, 1 indicates the delivery end of the refining-chamber of a glass tank furnace. This may be of more or less ordinary construction, and is provided with an opening 2. Located in the outlet is a 60 siphon member 3, which spans the wall of the refining-chamber and delivers the glass to a pot or receptacle 4. The pot 4 may be adjustable up and down, and for this purpose has attached to it three supporting-rods 5 65 (only two of which are shown in the sectional drawing), which rods are screw-threaded as at 6. The said rods pass through supporting-beams 7, which in turn are mounted upon a framework 8 having suitable supports 9. The threaded ends of the rods 5 are engaged by nuts 10, which have sprocket-wheels secured thereto and a sprocket-chain 11 passes from one of said wheels to the other, one of said nuts being provided with a hand-wheel 12, by which all may be operated to raise and lower the pot 4.

The siphon-tube 3 is provided with a suction connection or passage 13, which in turn 70 communicates with a passage 14 in a suction connection 15, with which communicates a pipe 16 leading to any suitable apparatus for producing a vacuum. This suction passage serves to start the siphon and maintain 75 the level of the surface of the glass within it at any desired point. The pot 4 is provided with a rib or dam 17 forming a pocket 18 around the outer leg of the siphon to hold a 80 mass of molten glass around this outer leg of the siphon to facilitate starting. When the glass within the pocket 18 is at the same level as that of the glass in the tank 1, there is no flow of glass from the refining-chamber to the pot 4. As soon, however, as the pot 4 is lowered so that the level of the glass within it is below the level of that in the refining-chamber, the glass passes through the siphon into the pocket 18 and thence 85 over the dam 17 into a second compartment 90 95 100

19 of the pot. This second compartment 19 is provided with an opening 20.

It is to be noted that there is no gravity flow of glass from the refining-chamber 1 into the pot 4, but the glass is transferred from the chamber to the pot only by the siphon action of the siphon-tube 3. To replace the glass flowing from the outer leg of the siphon, glass is elevated or transferred by suction or reduction of atmospheric pressure in the siphon 3 from the tank into the siphon. Whenever this siphon apparatus ceases to operate, there is no further discharge of glass from the tank through the siphon into the pot 4, and this is the normal condition in which the siphon remains during idle periods of the apparatus.

The advantages of this arrangement are many; incidentally, it enables a user to replace the spout-plug 21 in which is formed a cavity or well having at its bottom an outlet here designated as 20 without having to freeze the glass in the compartment 19; there being no outflow from the tank, it is practical to install the apparatus without stopping the operation of the tank.

Within the pot 4 is mounted a tube or hollow plunger 22, which conveniently may pass freely through an opening 23 in the top of the pot. This plunger is made of clay or other refractory material to obviate the deleterious action of the molten glass and of the temperature within the pot. The upper end of the plunger or tube 22 may be enlarged slightly to form a shoulder 24 to receive a clamping means 25 for clamping a metal plate 26 over the top of the pipe or tube to which plate is threaded or otherwise secured a pipe 27, which, through a flexible connection 28, leads to a connection 29, which is in communication with a source of vacuum, the vacuum connection being controlled by a valve 30 having an operating lever 31. A second connection of the flexible pipe 28 is made at 32 with a pipe 33, which is in communication with a suitable source of pressure. This pressure connection is controlled by a second valve 34 having an operating lever 35.

Thus it will be seen that the tube 22 within the pot 4 may be placed in communication with a source of vacuum or a source of pressure, as desired, to accomplish purposes hereinafter specified.

The tube also is provided with means by which it may be raised or lowered within the pot to vary the distance of its lower end from the outlet 20 of the pot. To this end a forked lever 36 is provided, which is pivotally mounted on a movable fulcrum 37, said fulcrum point being supported on an arm 38 pivoted at 39 on a fixed bracket 40 secured to the framework 9. This fulcrum-arm 38 has an extension 41 provided with an arcuate slot 42 engaging a bolt and lock-nut 43 by

which the fulcrum-arm 38, the fulcrum 37 and the lever 36 may be held adjusted in different fixed positions. The outer end of the lever 36 is pivotally connected at 44 with a rod 45, which rod is provided at its lower end with an eccentric strap 46 engaging an eccentric 47 mounted on a shaft 48. The shaft 48 may be rotated from any desired source of power. Thus it will be seen that upon rotation of the shaft 48, the tube 22 may be raised or lowered intermittently through the connections specified. The connection 44 is screw-threaded upon the vertical rod 45 and the position of the connection upon the rod is fixed by means of a lock nut 45a. This arrangement provides a means for adjusting the degree of vertical movement of the tube 22 in addition to the adjustment provided by the arm 38.

Thus it is seen that the plunger is given a reciprocatory movement through a lever whose fulcrum and point of application of power comprise movable pivots which are capable of adjusting movement relative to each other.

At temperatures necessary for working, molten glass is a stiff viscous fluid tenaciously adhering to any hot material. The flow starts by forming a half globular drop at the orifice of the vessel; next, its adhesion to the edges of the orifice causes the drop to pull downward at the center, usually forming a drop, the upper end of which adheres to the orifice and the center pulls away to a small stream or thread and this attenuated condition remains constant. Glass resembles all other viscous fluids in this respect, but shows a very great contraction in area of stream.

If the head or level of the glass in the supply reservoir be increased or more pressure applied to the surface of the glass, this contraction below the orifice will be reduced. This is due to the fact that the adherence to the edge of the orifice is so much greater than the tension of the glass particles to each other, and greater pressure forces more glass through the center of the drop without increasing to any great degree the flow at the edges or outer sides of the drop. Conversely, by decreasing pressure on the head or level of the glass, contraction of the stream is increased, and by varying the rate of flow, it is possible to so expand or contract the section of stream near the orifice as to make it resemble within narrow limits, a predetermined form. Also by cutting off the issued glass close to the orifice the contracted section (or the tail part above the shears) will be drawn up into the half globular drop at the orifice by reason of the law that a drop of any fluid tends to assume a globular form up to the disrupting point, and corrects any deviation of form by drawing to it the distorted part by molecular attraction of its particles. This forms independent masses without support.

ing the stream on the shears or other cold members.

In the method employed in carrying out my invention, no forces operate upon the glass in its line of flow from the tank or other source of supply to the discharge opening, but instead forces act upon the glass at or beyond the orifice, (as the term orifice is defined herein) and act in such a way as to accelerate the normal flow and not to stop it, so that by varying the amount of these forces, variation in the normal rate of flow is obtained.

This acceleration at or beyond the orifice is produced by the force of tension among the particles of the glass, and is applied after the glass leaves the orifice. This force of tension is very great in thick viscous liquids, such as glass at working temperature.

The force of varying pressure is applied to the drop after it is formed and is used to correct the shape of the issued glass independent of the force of gravity, which is the sole force which ordinarily acts to shape the drop at or after it has passed the opening.

Figs. 3 to 7 illustrate in detail the general operation of the apparatus,—insofar as it concerns the flow of the glass from the pot in the forming of the gather or gob,—and also show the control of the formation of the gather or gob.

Assuming that the pot 4 contains glass at the proper level for the operation of the apparatus, as shown, for example, in Fig. 1, and a gather or gob is about to be formed, the tube or plunger 22 is in the position indicated in Figs. 1, 3, 5 and 6, and the shears, which are indicated diagrammatically at 49, are open. With the parts in this position, the tube 22 forms with the walls of the cavity or well above the pot-opening 20 a discharge orifice, which is clearly shown at 50. At this point, I desire to draw attention to the clear distinction which I make between the opening 20 of the pot and what I here term as my "discharge orifice", or that passage for the molten glass where the glass after passing the orifice 50 is relieved of the pressures due to head or gravity influences of the mass of glass within the pot. This distinction must be clearly borne in mind in reading the following description of the operation of the apparatus, the term "outlet" on the one hand, referring to the opening 20 in the bottom of the pot; and the term "orifice", referring to the passage 50 between the lower end of the tube 22 and the walls of the cavity or well above the pot-opening 20. Also I make a distinction between this orifice 50 and the opening or passage 22' in the tube 22, which opening 22', like the pot-opening 20, does not affect the glass until after it has passed the orifice 50, but merely directs the course of the glass after it has left the passage 50.

In the ordinary operation of the device, the

tube 22 may be in the position shown, for example, in Figs. 1, 3, 5 and 6; and even slightly above the bottom of the pot;—or, on the other hand, this tube may, if desired, project down to a point beyond the lower end of the pot-opening, as shown in Figs. 9 to 13, inclusive. In either case, the mode of operation of the device is substantially the same. When vacuum or suction is applied through the tube 22, the glass is drawn up inside the tube, as shown at 52 in Figs. 1, 3 and 13. It is to be understood that the relative diameters of the opening 20 and of the pipe 22 are such that the sucking-up action into the tube 22 cannot and does not stop normal flow of the glass down through the orifice 50 between the walls of the cavity or well above said opening 20 and the walls of the tube 22. In other words, the parts are so proportioned that no matter how rapidly glass may be sucked up into the tube 22, this has no tendency to check or retard the flow of the glass down through the orifice 50. On the contrary, the only effect which sucking-up of the glass into the tube 22 may have is that flow of the glass out through the orifice 50, as distinguished from the pot-opening 20, may be thereby accelerated, but it is never checked. It will be obvious that this condition of acceleration of the flow of glass down through the orifice caused by the suction in the tube 22 will take place both when the pipe is slightly elevated above the opening 20, or even though the tube is depressed below the opening 20. With the parts properly proportioned, it is clear that the sucking-up action of the tube 22 may take place in such way as simply to cause the acceleration of flow between the edge of the tube and the edge of the pot-opening.

In using this apparatus, the glass flowing down through the orifice first assumes the more or less globular shape, shown at 53, Fig. 9. At the same time that this initial flow takes place, a certain amount of glass may be drawn up into the tube 22, as shown at 54, Fig. 9. Then, as the flow continues out through the orifice 50, and when the globule 53 elongates, as at 55, Fig. 10, and thereby tends to become attenuated or thin,—the glass in the tube 22 may be forced out as shown at 56, Fig. 10, to fill in the center of the globule and cause the globule to assume substantially the form shown at 55, Fig. 10. Continued expulsion of the glass from the tube 22, as illustrated at 57 in Figs. 5 and 11, causes the globule to maintain substantially a uniform diameter, as shown at such points 57 in Figs. 5 and 11, so that we then have a mass of glass ready for discharge into a mold 125 or the like, which is of substantially uniform diameter and of practically predetermined shape and mass.

When, now, it is desired to cut off this freely hanging mass to deposit the same in 130.

the mold, the sucking action into the tube 22 may be resumed, as shown at 58 in Fig. 12, and it may be made sufficiently rapid to cause a decided contraction in the glass at the point 59, Fig. 12. It will be understood, however, that the flow of the glass down through the orifice 50 has not thus been checked, but after the glass has passed into and partially out of the orifice 50, it is drawn up into the tube 22, instead of being supplied to the completed globule 60. The globule is then cut off at the point 59 in the ordinary manner,—as shown at 61, Fig. 6,—by means of the shears 49. At this stage of the proceedings, one of the 15 principal advantages of this invention comes into play which is the taking care of the chilled part of the globule, which is cut off by the cutting shears. This chilled part is indicated as located at the point 62, Figs. 3, 20 6 and 13.

It is obvious that the sucking action of the tube 22 draws upon the glass after it is flowed down past the lower end of said tube 22, and any of the glass which lies below the lower 25 end of this tube tends to be sucked up into the tube under the action of the vacuum. This action, therefore, is illustrated in Figs. 3, 6 and 13, in which it is seen that the stub left by the cut, tends to be drawn up into the tube 22 and, therefore, the chilled portion 62, which was that part which contacted with the shears when the first charge was cut off, is drawn up into the tube 22; but, at the same time, the glass continues to flow from 30 the orifice of the vessel down and around the lower end of the tube 22 and, consequently, this fresh-flowing hot glass completely surrounds and incorporates the chilled part 62 into the center of its mass, or else so stretches 35 and kneads this chilled part as to distribute or stretch it over that part of the surface of the drop removed from the point of the drop. By this stretching action, this chilled part is re-heated by the body of the glass. 40 Thus when the second charge is formed, and the glass is again expelled from the tube 22, this chilled portion will likewise be expelled into the center of the mass of the forming charge or stretch over it, and will become assimilated and incorporated in it in such a way 45 that it will not detrimentally affect the homogeneity of the glass in said charge.

In extremely large gathers or where the glass becomes quite stiff, a small flame can be 50 directed against the suspended gather 57 so that the point of the gather can be slightly re-heated and thus reenforce the other agencies for the removal of the chilled spot. This arrangement is shown in Fig. 15 where 55 the small flame 80 is projected against the gather by means of a burner 81 controlled by a valve 82.

It will be seen, therefore, that by this method practiced by the apparatus thus far 60 described, while the flow of the glass out

through the orifice 50 of the pot may be accelerated beyond the normal rate at will, it cannot be checked to a point below the normal rate of flow.

By increasing the speed of the glass, either 70 when rising or falling in the tube 22, a method is provided for increasing the normal rate of flow and for thus providing a regulating means for equalizing variations due to changes in the level of the glass in the pot 75 or container, or due to changes of temperature in the glass, both of which would affect the normal flow from the reservoir out through the orifice.

It will be understood that the varying of 80 the suction or pressure within the plunger or tube 22 is effected by the properly timed operation of the valves 30 and 34 of the pipes 29 and 33, respectively. For this purpose the operating lever 31 of the valve 30 is connected to a rod 68, which has at its lower end an anti-friction roller 69 bearing on a cam 70. The rod 68 passes through a guide-sleeve 71, and has surrounding it below said guide-sleeve a spring 72, which holds the 90 anti-friction roller 69 in contact with the cam 70. The operating-lever 35 of the valve 34 is connected by a rod 73 in a similar manner with a second cam 74, and is held in contact therewith in the same way, the cams 70 and 74 being fixed on the shaft 48. As this shaft rotates, therefore, the communication with the source of vacuum and the source of pressure will be properly timed for the operations intended.

It is to be understood also that the shears 49 are operatively-connected with actuating mechanism so that said shears will be operated in synchronism with the forming of the drop or gob, and will cut off the gobs in proper succession and at proper times determined by the forming of the gob, which is, in this case, under the control of the operator; that is to say, gobs of greater or less length may be formed, and in other respects the character of the gob may be varied to suit the particular purpose for which it is to be used.

Now referring to the raising and lowering of the tube or plunger 22, its raised position is indicated in Fig. 4 of the drawings. This raising and lowering is controlled by the lever 36, and its operating mechanism heretofore described.

It is to be understood that this raising and lowering of the tube is not intended for the purpose of disposing of the chilled spot on the gob, but it is to be employed in the first place for the delaying of the formation of the gob, which is accomplished by raising 120 the tube; and, second, for adding to the acceleration of the glass to form in some instances a larger gob through the same diameter of pot-opening; that is to say, in lowering the tube. In any event, however, it is 125 130

to be understood that the sucking-up of the chilled part of the gob is first performed by the sucking action of this tube when in its lowermost position as that is the effective position for this action. In order that the pipe may always assume its most effective lower position, but at the same time, in order that the travel of the tube may be increased or diminished as desired, I provide the movable fulcrum 37 for the lever 36,—it being understood that in any adjusted position of this fulcrum, the tube will always seek approximately the same lowermost position with respect to the bottom of the pot, but its travel may be increased or diminished by such adjustment. Therefore, in employing this up and down movement of the tube as an adjunct to its normal action in accelerating the feed of the glass, it is first held at its lowered position after a gob has been cut off to suck up the chilled portion of the following gob. This sucking action also retards the formation of the following gob, which retardation is increased by then raising the tube. It will be noted at this point that the raising of the tube has increased what was formerly the orifice, and allowed for a greater flow of glass through the opening in the bottom of the pot. When the retardation period has extended for the desired time, the tube is again lowered and in so lowering, it accelerates the flow of the glass out through the opening in the bottom of the pot. When the tube is in its lower position, expulsion of the glass within the tube again fills the middle or body of the gob as heretofore described. This function of the tube 22 may be effectively employed in the forming of unusually large gobs for the fabricating of large articles, but it is to be understood that such up and down movement of the tube may be also employed effectively in the formation of small articles, the extent of travel of the tube being determined to some extent by the size of the article to be fabricated.

The travel of this tube has the further function that when the temperature of the glass in the vessel falls for any reason, and the glass becomes more viscous, the downward movement of the tube assists in the expulsion of the glass through the opening in the bottom of the pot, thus compensating for the cooling and consequent less workable condition of the glass by the vacuum and pressure action of the tube, and this effectiveness of the travel of the tube increases as the glass becomes colder. Conversely, as the glass slowly resumes a higher temperature, it follows that this plunger action of the tube becomes less effective in the more fluid glass, while at the same time, the suction and pressure action within the tube become the more effective on the more fluid or hotter glass; therefore, it will be seen that the travel of the tube and vacuum and pressure action

within the tube practically stabilize each other in their ultimate effect.

In Fig. 14 is shown a modified form of the apparatus using the same principle, but in this case the auxiliary member or tube takes the form of a laterally-extending passage 63, formed in an offset 64 of the reservoir or pot 4, and connected by a passage 65 with the source of vacuum. The lower end 66 of this auxiliary passage adjoins that of the orifice 50' from the tank 4. In this case, the auxiliary member or passage 63 takes the glass from and adds it again to the sides of the drop instead of feeding it directly to the center, but the chilled spot caused by the shearing-off of the previous drop is effectively incorporated into the mass of the following mass or charge, and is further removed from the lower end of the charge, which is the critical location when feeding the glass to a mold.

In Fig. 8 is shown another modified form of the apparatus using the same principle, but in this case the auxiliary member or tube takes the form of a lateral horizontal passage 66, which is mounted just below the orifice 50² in the bottom of the vessel 4. This passage 66 communicates with a suction-tube 67 connected with any suitable source of pressure-varying or suction means. In other respects, however, the operation of this modified apparatus is precisely the same as that heretofore described.

It is to be noted that the pot 4 here shown is in communication with the heat of the gases of the tank 1 through the passage or opening 2. Should it be necessary, however, to add additional heat to the interior of the pot, the same may be done by introducing a suitable source of flame or heat through an opening, such, for example, as the opening 75, Fig. 1.

The invention herein described is not limited as regards the broad terms of the claims to any particular construction or arrangement of mechanical devices, whereby the rate of flow or shape of the drop are affected by forces acting on the glass at or outside the orifice of the container, so as to increase such normal flow by pulling the glass through the discharge or outlet.

There are two distinct characteristics of my invention: First,—that the normal flow can be increased by force acting on the flow at or after it leaves the outlet; and, second,—that the section of the stream or shape of the glass can be varied without stopping or reversing the normal flow from the supply reservoir in the discharge opening, and without varying either the pressure upon or height of the surface level of the glass in any part of the supply reservoir. On the contrary, the entire action takes place on the glass after it has flowed slightly beyond the mass of glass in the container and the force applied

to the flowing glass is expended entirely on the glass after it has passed beyond the influence of the glass in the container.

This application is a continuation in part 5 of my copending application, Serial No. 110-676, filed July 22, 1916, now Patent No. 1,315,668.

While I have herein described particular forms of apparatus by which my invention 10 may be carried out, it is to be understood that the invention is not limited in any manner to such particular apparatus, but that the apparatus for and the method of carrying out the invention may be varied to any desired extent within the scope of the appended 15 claims.

What I claim is:

1. In apparatus of the class described, the combination of a container for molten glass 20 having an outlet for discharging the glass in successive suspended masses and fluid-pressure means located entirely above the outlet for transferring a connected portion of the glass to an auxiliary member after leaving 25 said container, said portion forming part of the next succeeding mass.

2. In apparatus of the class described, the combination of a container for molten glass 30 having an outlet for discharging the glass in successive suspended masses, and fluid-pressure means located entirely above the outlet for supporting a connected portion of the glass while permitting the discharge of glass from said container, said connected portion 35 forming part of the next succeeding mass.

3. In apparatus of the class described, the combination of a receptacle for holding molten glass, said receptacle having an impulsion chamber or well terminating in a discharge 40 outlet, a reciprocable plunger adapted to enter said well, means for reciprocating the plunger, fluid pressure means cooperating with said plunger for forming a mass of glass of controlled selected shape in free suspension 45 below said receptacle, and mechanical shears so timed and operated as to sever the suspended mass while it retains the selected shape so imparted to it.

4. Apparatus for feeding molten glass comprising a supply reservoir having a well terminating in a discharge outlet and means extending into the well and terminating above the outlet for applying fluid pressure to the glass flowing through the said outlet without varying the level of the surface of the glass within the said supply reservoir.

5. Apparatus for feeding molten glass comprising a supply reservoir having a discharge outlet in its bottom, means including a hollow member extending into the glass and terminating above the discharge outlet for directly applying to the glass above the outlet and axially of the outlet pneumatic extrusive force at such times and in such amounts as to 65 cause the glass to assume while freely sus-

pended from the outlet a definite selected artificial shape, and severing means timed to sever the glass while it maintains substantially the shape so selected and produced.

6. In glass-delivering apparatus, the combination of a receptacle for holding molten glass, said receptacle having a discharge outlet, a reciprocable plunger, fluid-pressure means cooperating with said plunger for forming a suspended mass of glass outside of 70 said receptacle, and shears spaced below the outlet for severing a mold charge from the suspended mass; the plunger, fluid pressure means and shears being so relatively timed as to impart to the mass while suspended a selected controllable shape and to sever a mold charge from the mass before control of the shape of the mass is lost.

7. Apparatus for feeding molten glass comprising a container for the glass having a well therein terminating in a discharge outlet, a refractory member adapted to move within said well and toward and from the outlet, means for imparting reciprocatory motion to said refractory member comprising a lever 85 fulcrumed upon an adjustably movable pivot, and means for moving said pivot to vary the stroke of said refractory member.

8. In a glass feeder in combination with a container for the glass having a submerged outlet, a plunger in adhesive contact with the glass and adapted to work in axial alignment with, and toward and from the outlet, a lever adapted to transmit reciprocatory movement to the plunger, an adjustably movable pivot 95 providing a fulcrum for said lever, and means for moving said pivot to vary the length of stroke of said plunger.

9. In a glass feeder in combination with a container for molten glass having a submerged outlet, an impelling member adapted to move to and from the outlet in axial alignment therewith, a lever for imparting movement to said impeller, an adjustably movable pivot adapted to act as a fulcrum for the lever, and means for moving said pivot to vary the upper position of the impeller without substantial change in its lower position.

10. A glass feeder comprising a container for the glass having a restricted well terminating in a discharge outlet, a controlling member in adhesive contact with the glass and operating within said well, but at all times out of contact with the walls thereof, a lever adapted to move the impeller periodically toward and away from the outlet, an adjustably movable pivot constituting a fulcrum for said lever, and means for moving said pivot to vary the character of the impeller movement within the well whereby the quantity of glass discharged from the outlet during each cycle of the impeller operation may be varied.

11. A glass feeder comprising a container for the glass having a submerged outlet, a re-

- ciprocating plunger adapted to move toward and from the outlet to control the formation of shaped suspended mold charges, a lever to impart reciprocatory movement to the plunger, means for applying power to said lever through an adjustably movable moving pivot, and means for adjusting the position of the pivot to vary the position of the plunger stroke to vary the size and shape of the glass charges discharged and suspended from the outlet.
12. In a glass feeder in combination with a container for the glass having a submerged outlet, a plunger adapted to move toward and from the outlet and in vertical alignment therewith, means for imparting movement to the plunger including a lever having a fulcrum point and a point of application of power adjustable with respect to each other, and means for adjusting one of said points to vary the length of the stroke of the plunger, and means for adjusting the other said points to vary the position of the stroke of the plunger.
13. In a glass feeder in combination with a container for the glass having a submerged outlet, a plunger adapted to move toward and from the outlet and in vertical alignment therewith, means for imparting movement to the plunger including a lever having an adjustably movable fulcrum and a movable point of application of power, and means for moving one of said points to vary the length of the stroke of the plunger.
14. The method of delivering molten glass from the outlet of a container, that comprises establishing a gravity flow of glass around the lower end of a hollow control member immersed in the glass and thence through the outlet effective while a substantial portion of the glass issues from the outlet, then increasing the rate of flow of further portions of the issuing glass, by a pneumatic impulse applied above the outlet, to a rate substantially equal to the then rate of downward flow of the previously issued portion, thereby shaping the glass while hanging freely into an elongated mass having the same or substantially the same cross sectional area for the greater portion of its length, severing a mold charge from the mass and thereafter receiving said charge in a mold.
15. The method of forming a mass of molten glass suitable when severed to form a mold charge and imparting a selected artificial shape thereto, that comprises forming a substantial portion of the mass by passing glass around the lower end of a control member immersed in the glass and thence through an opening in the bottom of a supply reservoir by gravity, forming a later substantial portion of the mass by forcing glass through said opening by a pneumatic impulse applied above the opening to accelerate the normal gravity flow, then contracting the cross sec-
- tion of the upper portion of the mass prior to its severance from the parent body, and severing the mass at the point of contraction while it is in suspension from the opening.
16. The method that comprises forming a suspended mass of molten glass by causing a substantial quantity of glass to flow around the lower end of a control member submerged in the glass and thence to issue by gravity through a submerged outlet in a container, and then forcing an additional substantial quantity of glass through the outlet into the interior of the mass of issued glass, while it is still suspended and hanging freely, by the local application of a pneumatic accelerating force to the glass issuing from the outlet sufficient to substantially overcome the tendency of the issued glass to contract.
17. The method of feeding molten glass in mold charges, which comprises passing the glass through an annular passage formed between the walls of a well in the bottom of a glass container and an implement projecting downwardly into said well, thence around the lower end of the implement and thence through the opening in the bottom of said container, controlling the rate of issue of said glass by varying pressure applied through said implement to the glass below the annular passage, and periodically severing mold charges from the glass so issued.
18. The method of feeding molten glass in mold charges, which comprises flowing the glass downwardly through a submerged outlet, periodically accelerating and retarding flow of glass through the outlet by communicating expelling and retarding pneumatic impulses to the glass above the outlet, further regulating flow of glass through the outlet by disposing a rigid implement in position to extend downwardly through the glass into the outlet without completely obstructing the outlet, and severing a mold charge from the issued glass in timed relation to one of said impulses on the glass.
19. The method of feeding molten glass in mold charges, which comprises flowing glass by gravity downwardly through a submerged outlet of a glass container, periodically accelerating and retarding flow of glass through the outlet by reciprocating an implement in adhesive contact with the glass substantially in line with the outlet, further accelerating and retarding flow of glass through the outlet by imparting expelling and retarding fluid impulses to the glass above the outlet in timed relation to the accelerating and retarding strokes of the implement, and periodically severing mold charges from successive masses of issued glass while such masses are suspended from the outlet.
20. The method of feeding molten glass in mold charges, which comprises flowing glass by gravity downwardly through a submerged

- outlet of a glass container, periodically accelerating and retarding flow of glass through the outlet by reciprocating an implement in adhesive contact with the glass substantially in line with the outlet, further accelerating and retarding flow of glass through the outlet by imparting expelling and retarding fluid impulses to the glass above the outlet in timed relation to the accelerating and retarding strokes of the implement, and periodically severing mold charges from successive masses of issued glass in timed relation to the application of the expelling fluid impulses and while such masses are suspended below the outlet.
21. The method of feeding molten glass in mold charges, which comprises flowing glass by gravity downwardly through a submerged outlet of a glass container, periodically accelerating and retarding flow of glass through the outlet by reciprocating an implement in adhesive contact with the glass substantially in line with the outlet, further accelerating and retarding flow of glass through the outlet by imparting expelling and retarding fluid impulses to the glass above the outlet in timed relation to the accelerating and retarding strokes of the implement, and severing mold charges from said suspended masses while such masses are suspended below the outlet and in timed relation to the application of the fluid expelling impulses.

In testimony whereof, I the said GEORGE E. HOWARD, have hereunto set my hand.
GEORGE E. HOWARD.
